UNITED STATES PATENT OFFICE.

GEORGE L. REICHHLEM, OF NEW YORK, N. Y., ASSIGNOR TO THE GASIFIER COMPANY, OF ELIZABETH, NEW JERSEY, A CORPORATION OF NEW JERSEY.

METHOD OF PRODUCING GAS.

Application filed November 15, 1920. Serial No. 424,069.

To all whom it may concern:

Be it known that I, GEORGE L. REICHHLEM, a citizen of the United States, residing at New York, in the county of New York and State of New York, have invented certain new and useful Improvements in Methods of Producing Gas, of which the following is a specification.

This invention relates to a method of and means for producing gas.

The object of this invention is to provide a simple, efficient, reliable and safe method of producing gas from raw fuel, such as oil and the like.

15 This and other objects are accomplished by means of the disclosure on the accompanying sheet of drawing, in which the single figure is a longitudinal vertical sectional view of my gasifier in connection with which 20 my method is practiced.

Referring to the drawing, it will be noted that the gasifier includes a base 10, to which is secured a main chamber 11. At the upper end of the base 10 a burner 12 is provided having an annular gas passageway 13 from which orifices 14 extend for directing gases into a main combustion chamber 15 formed by an annular wall 16 having at its upper cone-shaped end a plurality of openings 17 to permit the escape of products of combustion into an annular vaporizing chamber 18 formed between the wall 16 and a second wall 19, both of which are located within the outer casing 11. The upper end 25 of the casing 11 is provided with a window 20 of mica, or any other suitable substance, which provides a peek-hole to observe the condition of the flame in the combustion chamber 15. The vaporizing chamber 18 is 30 provided with a helical shelf 21, the upper end of which communicates with an oil supply 22, which oil is to be converted into a gas in a manner to be described hereinafter, the gas passing from the vaporizing chamber 18 through an opening 23 in the lower part 35 of the wall 19 and out through a pipe 24 to a communicating connection 25, to which air is supplied through a pipe 26 so that the gas and air may be mixed for use in a furnace or engine. A small amount (about two percent) of the generated gas is drawn out of the pipe 24 through a pipe 27 by the action of air passing through a valve controlled pipe 28, the mixture of air and gas 40 being supplied to the annular gas chamber

13 from which the gas passes through orifices 14 and is ignited at the burner for heating the walls 16, 19, and helical shelf 21, and producing products of combustion for a purpose to be considered hereinafter. 60 The base is provided with a burner in the form of a pipe coil 29, having a plurality of apertures 30 through which a mixture of gas and air may pass, the gas being provided from any suitable source 31 and the air being supplied through a pipe 32 and mixing with the gas in pipe 33 to form a combustible mixture.

In starting to operate the gasifier a cover 34 for the base is temporarily removed for 70 the purpose of inserting a torch, or the like, for igniting the combustible mixture passing through the apertures 30. To direct the flame an air supply is provided through a valve-controlled pipe 35, said pipe terminating in an upwardly extending portion within the middle of the coil 29. As a result of this arrangement the flame caused by the passage of gas through the apertures 30 is shot upwardly through the openings 80 36 in a cap 37 screwed into the burner 12, this flame heating the burner 12 and initially heating the walls 16 and 19 and helical shelf 21, and furnishing products of combustion. After the burner is properly heated, oil is 85 permitted to flow from the supply source 22 on to the helical shelf 21. As a result of the walls 16 and 19 and the shelf 21 being heated, the oil which is supplied to the latter is vaporized, the vapor tending to 90 gravitate or move downwardly through the winding passageway between portions of the shelf toward the outlet 23. Under given conditions the oil supply to the shelf 21 would leave a residuum of carbon or a carbon deposit, depending upon the temperature 95 of the shelf, but the products of combustion from the combustion chamber 15, which pass outwardly through the apertures 17, sweep the vapors from the shelf, carrying them 100 down in their natural direction, that is, downwardly, since these vapors are heavier than air, especially in the case of the relatively heavy fuels. The resultant mixture formed in the vaporizing chamber 19 passes 105 outwardly through the pipe 24. When the valve 38 in the air line 28 is open, air is forced therethrough for drawing off a certain amount of gas from the pipe 24, the air and gas mixing to form a combustible mix- 110

ture which is ignited in passing through the orifices 14 of the burner 12. The gas supplied to the burner 12 is the main supply for heating the walls 16 and 19 and the shelf 21 and for providing the products of combustion, which pass downwardly through the vaporizing chamber 18. It will be understood that the gas which is formed in the vaporizing chamber 18 is very rich and 10 will not in such condition support combustion, and, as a matter of fact, substantially no oxygen is carried into the vaporizing chamber 18 because the oxygen passed into the combustion chamber 15 is substantially 15 completely consumed before it passes into the vaporizing chamber 18, and if any oxygen were left in the products of combustion, it would be taken up and enriched so rapidly in the vaporizing chamber as to 20 make combustion in said chamber absolutely impossible. This main supply of gas generated in the vaporizing chamber 18 is then 25 passed off through the pipe 24 into the connection 25, where it is mixed with air passing through pipe 26 for providing a combustible mixture to be used in any desired manner. The gases of combustion passing from the combustion chamber 15 to the vaporizing chamber 18 serve first to heat the 30 walls 16 and 19 and shelf 21 to the proper degree for vaporizing the fuel or oil supplied to the helical shelf 21. The products of combustion also act as a vehicle in that the products of combustion sweep the vapor 35 from the helical shelf 21 and prevent the deposit of carbon. These products of combustion contain substantially no free oxygen and accordingly in sweeping over the helical shelf 21 the vapors are taken up by the 40 gas before same are heated to a temperature sufficient to make a deposit. The products of combustion also serve to furnish the heat for fixing the gas formed by the mixture of the vapor generated in the vaporizing 45 chamber 18 and the products of combustion supplied thereto. Accordingly, in its simplest terms I accomplish the following: First, the expanding of the fuel into vapors; second, causing products of combustion to 50 sweep over the helical shelf to prevent the deposit of carbon from the vapors; third, causing the vapors and products of combustion to mix to form a mixture which is heated by the products of combustion to the point 55 of fixing. It will be understood that if the temperature of the resultant mixture of vapor and products of combustion is not raised to a certain predetermined point, the mixture will be a vaporous one. Accordingly, the condition of the mixture may be 60 controlled, a given temperature being provided if a vaporous mixture is desired, and a higher temperature provided if a fixed mixture is desired.

65 There may be various modifications of

my invention herein disclosed, and it is my intention to cover all such modifications which do not involve a departure from the spirit and scope of the following claims.

I claim:

1. The method of producing gas from a low grade hydrocarbon fuel which consists in applying said fuel to a heated surface and propelling the resulting vaporized fuel with a gravitational sweeping movement of 70 constantly changing direction, free of abrupt bends, along said surface by means of a hot combustion gas, whereby to prevent the deposit of carbon.

2. The method of producing gas from raw 80 hydrocarbon fuel consisting in vaporizing said fuel and causing a gravitational flow in a constantly changing direction, free of abrupt bends, of the resulting vapor in and by a moving combustion gas to prevent de- 85 posit of carbon.

3. The method of producing gas from hydrocarbon fuel consisting in vaporizing said fuel, causing a gravitational movement in a constantly changing direction, free of 90 abrupt bends, of said vapor by and in a vehicle comprising a moving combustion gas to prevent the deposit of carbon, and heating the vaporized fuel during said gravitational movement.

4. The method of producing gas from hydrocarbon fuel consisting in vaporizing the fuel and causing a gravitational movement in a constantly changing direction, free of abrupt bends, of said vaporized fuel in 100 and by a vehicle of combustion gas while said vaporizing is being accomplished to prevent the deposit of carbon.

5. The method of producing gas from hydrocarbon fuel consisting in vaporizing 105 the fuel, mixing products of combustion therewith, directing said vaporized fuel and said products of combustion with a gravitational movement, free of abrupt bends, in a constantly changing direction, and burning air with a portion of the resultant mixture to provide the source of said products of combustion.

6. The method of producing gas from hydrocarbon fuel consisting in vaporizing 115 said fuel by means of heat, causing a gravitational flow, free of abrupt bends, in a constantly changing direction, of said vapor in a rich non-combustion supporting condition, and providing products of combustion for 120 propelling said rich gas in said gravitational flow.

7. The method of producing gas from hydrocarbon fuel consisting in vaporizing said fuel by means of heat, causing a gravitational flow in a constantly changing direction, free of abrupt bends, of said vapor in a rich non-combustion supporting condition, providing products of combustion for propelling said rich gas in said gravitational 125

flow, and mixing a limited amount of air with a portion of said rich gas for providing said products of combustion.

8. The method of producing gas from hydrocarbon fuel consisting in vaporizing the fuel, mixing products of combustion therewith, and directing said vaporized fuel and said products of combustion with a gravitational movement, free of abrupt bends, in a constantly changing direction.

9. The method of producing gas from a low grade hydrocarbon fuel which consists in producing products of combustion to provide a gaseous propelling vehicle and to provide heat, vaporizing low grade hydrocarbon fuel by means of said heat, and causing said gaseous vehicle to propel said vaporized fuel with a gravitational movement in a constantly changing direction, free of abrupt bends, to prevent the deposit of carbon.

10. The method of producing gas from hydrocarbon fuel which consists in heating a surface by burning a fuel in proximity to said surface to produce a gaseous vehicle and to heat said surface, applying said hydrocarbon fuel to said heated surface to vaporize said fuel, and causing said gaseous vehicle to propel said vaporized fuel along said heated surface with a gravitational movement, free of abrupt bends, in a constantly changing direction.

11. The method of producing gas from a low grade hydrocarbon fuel which consists in vaporizing said fuel by applying the hydrocarbon fuel to a heated surface, propelling said vaporized fuel with a gravitational movement of constantly changing direction,

free of abrupt bends, by means of a gaseous medium, mixing a predetermined amount of air with a portion of the resulting gas, and burning said air and gas mixture to produce a continuous supply of gaseous medium and for keeping said surface in a heated condition.

12. The method of continuously producing gas from low grade hydrocarbon fuel, consisting of vaporizing said fuel, propelling the resulting vapor by means of a combustion gas with a gravitational movement, free of abrupt bends, in a constantly changing direction, and subjecting said vapor to heat.

13. The method of producing gas from raw hydrocarbon fuel consisting in applying said fuel to a hot surface and propelling the resulting vaporized fuel with a gravitational movement in a constantly changing direction, free of abrupt bends, by means of a gaseous medium, which gaseous medium is obtained by the combustion of part of said vaporized fuel with air.

14. The method of producing gas from raw hydrocarbon fuel consisting in vaporizing said fuel and propelling the resulting vapor in a helical movement, free of abrupt bends, using a combustion gas for propelling said vapor and using part of said treated vaporized fuel in combination with air to provide said combustion gas, and applying the heat from said combustion gas centrally of said helical movement.

Signed at New York, New York, this 10th day of November, 1920.

GEORGE L. REICHELIM.
